(57) **CLAIM**

The ornamental design for a safety gate, as shown and described.

DESCRIPTION

FIG. 1 is a top, front, right-side perspective view of a safety gate showing our new design;

FIG. 2 is a top, rear, right-side perspective view thereof;

FIG. 3 is a front elevational view thereof;

FIG. 4 is a rear elevational view thereof;

FIG. 5 is a left-side elevational view thereof;

FIG. 6 is a right-side elevational view thereof;

FIG. 7 is a top plan view thereof;

FIG. 8 is a bottom plan view thereof; and,

FIG. 9 is a perspective view, with the door open, in an alternate condition of use.

The broken lines shown in the drawings depict portions of the safety gate that form no part of the claimed design.
